PANEL

August G. Trometer, Sturgis, Mich., assignor to
Gibson Refrigerator Company, Greenville,
Mich., a corporation of Michigan

Application July 5, 1952, Serial No. 20,488

Term of patent 7 years

(Cl. D62—4)

To all whom it may concern:

Be it known that I, August G. Trometer, a citizen of the United States, residing at Sturgis, in the county of Saint Joseph and State of Michigan, have invented a new, original, and ornamental Design for an Insert Grille for an Air Conditioner Panel, of which the following is a specification, reference being had to the accompanying drawing, forming a part hereof.

In the drawing:

Figure 1 is a plan view of an insert grille for an air conditioner panel, showing my new design;

Figure 2 is an enlarged sectional view of the insert grille taken on the line 2—2 of Figure 1; and

Figure 3 is an enlarged sectional view of the insert grille taken on the line 3—3 of Figure 1.

I claim:

The ornamental design for an insert grille for an air conditioner panel, as shown.

AUGUST G. TROMETER.
